G. M. LEWIS

COAL OR WOOD CARRIER

Filed Jan. 9, 1922

G. M. Lewis

By Watson E. Coleman
Attorney

UNITED STATES PATENT OFFICE.

GRACE M. LEWIS, OF KEENE, NEW HAMPSHIRE.

COAL OR WOOD CARRIER.

Application filed January 9, 1922. Serial No. 528,003.

To all whom it may concern:

Be it known that I, GRACE M. LEWIS, a citizen of the United States, residing at Keene, in the county of Cheshire and State of New Hampshire, have invented certain new and useful Improvements in Coal or Wood Carriers, of which the following is a specification, reference being had to the accompanying drawings.

10 Heretofore in houses where the ranges and latrobes are located on the first floor it is necessary to manually carry coal or wood from the basement or cellar, and place it in a box or other receptacle to the side of the 15 range or latrobe. This arrangement makes considerable litter or debris around the range or latrobe, and also the box is more or less a catch-all. This arrangement also necessitates considerable work on the part of 20 the attendant of the range or latrobe, and also entails keeping the box in repair.

The present invention has for its purpose the provision of an elevator carrier arranged between the basement or cellar and the first 25 floor, whereby the coal or wood may be elevated to a position adjacent the range or latrobe or other heating or cooking apparatus, so that the attendant may, at all times, have a ready supply.

30 Another purpose is to obviate the foregoing disadvantages and at the same time provide an apparatus, so constructed and arranged that the wood and coal, as well as the container or carrier are invisible, and will 35 not catch the debris and the like. The container or carrier may hold a sufficient supply of wood or coal, to permit the attendant to keep the fire burning for a day or more.

Still another purpose is the provision of a 40 passage way, or shaft, in which the carrier or container is mounted for vertical movement, in combination with means located in the basement or cellar and operatively connecting with the carrier or container, for causing its ascension to the first floor or to any other point, where the coal or wood 45 is to be used for keeping the fire burning.

A further purpose consists in the provision 50 of a container or carrier having an inclined bottom, so that the coal or wood, preferably the former, may be automatically discharged from the container or carrier when elevated to the first floor and when the door of the passage way or shaft is opened.

Still a further purpose consists in the provision of a container or carrier provided with an outlet opening together with the hinged door fitting within the opening when closed and having side flanges, whereby when opened and disposed in an inclined position may act as a chute, to permit the discharge of the coal very easily into a receptacle for emptying in the range or latrobe.

Additionally the invention aims to provide means for elevating the carrier or container, and means for holding the carrier or container in an elevated position.

While the design and construction at present illustrated and set forth are deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features and combination of parts, as will be hereinafter set forth, shown in the drawings and claimed.

In the drawings:

Figure 1 is a view in section showing the basement or cellar, and the first floor of a dwelling, showing the improved carrier applied, the lower part of the shaft or passage way being open, while the upper part is encased in the wall;

Figure 2 is a vertical sectional view on line 2—2 of Figure 1;

Figure 3 is an enlarged detail view of the carrier or container, showing the door or closure thereof open, whereby the coal may discharge therefrom;

Figure 4 is an enlarged detail sectional view through the drum which operates the elevator or container cable, showing the hand wheel which operates the drum, and also the ratchet for holding the drum against retrograde movement.

Referring to the drawings, 1 designates the wall of a dwelling or house, wherein, at a point adjacent the usual chimney a passage way or shaft 2 is constructed. This passage way or shaft acts as a guide for the container or carrier for the coal or wood.

Mounted in suitable bearings 3 at the top of the shaft or passage way on the beams 4 is a shaft 5 carrying a pulley 6, over

which a suitable cable, chain or the like 7 engages. One end of this chain connects to a ring 8, which is located on the top of the coal carrier or container 9, which is mounted 5 for movement in the shaft or passage way 2.

This container or carrier may be constructed of any suitable material preferably sheet metal or the like, and may be made any suitable size, it depending upon the supply 10 of coal or wood to be carried to the first floor, sufficient for lighting the fire for twenty-four hours, more or less. This container or carrier is provided with an inclined bottom 10, and has the upper part of 15 its front portion open, to permit the carrier to be easily filled in the basement or cellar. The lower part of the front portion of the carrier has a front wall 11 provided with a discharge opening 12, to the lower edge of 20 which a combination closure and chute 13 is hingedly mounted as at 14. This closure or chute 13 fits within the wall of the opening 12, and is provided with side flanges 15, which, when the chute or closure is lowered, 25 as shown in the drawings, act as guides for the coal, keeping the coal from running off the sides of the chute or closure. It will be noted that the bottom 10 is inclined, therefore the coal or the like that is elevated 30 from the basement or cellar will discharge with considerable force through the chute or closure.

The front wall of the upper closed part of the shaft or passage way (which is constructed preferably adjacent the chimney of the house or dwelling) is provided with an opening 16, which is lined with a suitable frame 17, to one edge of which as at 18 is a closure 19. This closure 19 has the usual 35 slide spring bolt 20, which engages the keeper 21 of conventional construction, for holding the closure 19 closed. The opening 16 is located at a position adjacent the range or latrobe, so that when the container or carrier is elevated, it will be in a close position to the range, sufficient to permit an attendant to open the door 19, then lower the closure or chute 13, and permit the coal or wood to discharge from the container or 40 carrier, into some other suitable receptacle, from which the attendant may deposit the coal or wood into the stove or range. The upper part of the shaft or passage way terminates a substantial distance above the 45 opening 16, therefore the pulley or wheel 6 is entirely out of sight.

The opposite side walls of the passage or shaft, at a point above the opening 16, but a substantial distance below the pulley 6, 50 are provided with abutments 22, such as cleats to limit the upward movement of the carrier or container, sufficient to permit the opening 12 to register with the opening 16, when the container is elevated.

65 Mounted in suitable bearings 23 rising

from the floor of the basement or cellar, is a suitable drum 24, about which the cable or chain 7 is wound. In fact the other extremity of the chain or cable is attached to the drum as at 25, so that when the drum 70 is rotated in the direction of the arrow *a*, the container or carrier may be elevated from the basement or cellar, to a position whereby the opening 12 may register with the opening 16.

The ends of the drum 24 are provided with cylindrical reduced portions 26, which are mounted in suitable ball bearings 27 of the brackets which rise from the floor of the cellar or basement.

80 The brackets each comprise the supporting portion 28, which is secured to the floor of the cellar or basement and the cap plate or strap 29, which is bolted to the transverse portion of the bracket as at 30. The transverse portion of the bracket and the cap plate or strap have opposite semi-circular bearings, provided with interior raceways, in which the anti-frictional ball bearings are mounted.

90 One of the cylindrical reduced portions 26 is provided with an extension 31, which is rectangular in cross section, and carries a hand wheel 32, with which a ratchet 33 rotates. Pivotally supported upon a lug 95 34 which is secured at 35 to one of the brackets is a pawl or dog 36, which cooperates with the teeth of the ratchet, for holding the drum against retrograde movement, particularly after the carrier or container has been elevated, whereby its discharge opening 12 may register with the opening 16.

100 In fact when coal, wood or the like is needed in the kitchen or upon the first floor where the latrobe is located, the attendant goes to the basement, and places the necessary supplies of coal or wood in the container or carrier. The handle of the hand wheel 32 is then grasped, and the wheel rotated, imparting movement to the drum which causes the cable or chain to wind thereon, until the carrier or container reaches a position above the first floor, where the abutments or cleats 22 will limit the 110 container or carrier in its elevated position. The pawl or dog will then prevent retrograde movement of the drum. The attendant then ascends to the first floor and the door 19 may then be opened, in which case 115 the coal or wood is allowed to discharge from the container or carrier through the door or chute 13, into a suitable receptacle. The attendant may then deposit the coal or wood into the range or latrobe.

120 The side flanges of the door chute are provided with slots 37, which are engaged by the spring catches 38 on the sides of the passage opening 12, for the purpose of keeping the door closure closed.

When the container or carrier is elevated, the cleats or abutments 22 act to limit the container to a position so that the discharge opening 12 of the container will register with the opening 16. Furthermore the opening 16 is of a size to permit the door chute to be lowered and extended through the opening, when the container is elevated, permitting the contents to easily empty into a suitable receptacle.

The invention having been set forth, what is claimed is:

1. In an apparatus for the purpose indicated, a passage way connecting the cellar and the first floor, the front wall of the passage way adjacent the first floor having a door controlled opening, a carrier operable vertically in said passage way and provided with an inclined bottom, said carrier having a discharge opening registerable with the opening of the passage way adjacent the first floor, and a door chute adapted to be lowered to a position in alignment with the inclined bottom and extended through the opening of the passage adjacent the first floor, whereby the contents of the carrier may discharge therefrom, said door chute having side flanges, to keep the contents from discharging to one side, said flanges having slots near their upper portions, and means on the sides of the discharge open-

ing of the carrier to engage said slots, to retain the door closure closed.

2. In an apparatus for the purpose indicated, a passage way connecting the cellar and the first floor, the front wall of the passage way adjacent the first floor having a door controlled opening, a container operable vertically in said passage way and provided with an inclined bottom, said container having a discharge opening registerable with the opening of the passage way adjacent the first floor, and a door chute adapted to be lowered to a position in alignment with the inclined bottom and extended through the opening of the passage adjacent the first floor, whereby the contents of the container may discharge therefrom, said door chute having side flanges, to keep the contents from discharging to one side, said flanges having slots near their upper portions, and means on the sides of the discharge opening of the container to engage said slots, to retain the door closure closed, and means for elevating the container including a ratchet disposed for preventing retrograde movement of said elevating means.

In testimony whereof I hereunto affix my signature.

GRACE M. LEWIS.
